UNITED STATES PATENT OFFICE.

DUANE LA DU, OF WARNER'S, NEW YORK.

DESIGN FOR A TYPE-HOLDER.

SPECIFICATION forming part of Design No. 33,167, dated September 4, 1900.

Application filed July 24, 1900. Serial No. 24,721. Term of patent 3½ years.

To all whom it may concern:

Be it known that I, DUANE LA DU, a citizen of the United States, residing at Warner's, in the county of Onondaga and State of New York, (and having his address at Warner's P. O., Warner's, New York,) have invented and produced a new and original Design for Type-Holders, of which the following is a specification, reference being had to the accompanying drawings, forming a part thereof, in which—

Figure 1 is a perspective view of the type-holder embodying my design. Fig. 2 is a sectional view taken on line 2 2, Fig. 1.
5 The leading or material feature of my design for type-holders consists of separated substantially-parallel outer and intermediate ribs $a\ a$ and a' and substantially-parallel lengthwise grooves or compartments $b\ b$ between the ribs, said ribs being united at their upper and lower ends by walls $b'\ b'$ and at their rear longitudinal edges by walls $c\ c$, as seen in the drawings. Flanges $c'\ c'$ extend laterally in opposite directions from the front 15 longitudinal edge of the intermediate rib a'

partially across the open front of the grooves $b\ b$, said flanges being of less length than the rib a' and terminating a short distance from the upper and lower walls $b'\ b'$. The rear walls $c\ c$ of the grooves $b\ b$ are also of less 30 length than the ribs $a\ a$ and a' , terminating at their lower ends a short distance above the lower end walls b' , as seen in Fig. 1.

This design presents a neat and characteristic appearance and when viewed in horizontal section, as seen in Fig. 2, has the appearance of two reversely-arranged inverted L's, having their bases united to the base of an inverted T. 35

Having thus described my invention, what 40 I claim, and desire to secure by Letters Patent, is—

The design for a type-holder as herein shown and described.

In witness whereof I have hereunto set my 45 hand this 13th day of July, 1900.

DUANE LA DU.
